 tion of Massachusetts

Application July 4, 1942, Serial No. 449,715

10 Claims. (Cl. 51—112)

The invention relates to lapping machines, and more particularly to a lapping machine having an automatic work loading mechanism.

One object of the invention is to provide a simple and thoroughly practical lapping machine for producing fine finishes on either flat or cylindrical work pieces between two opposed relatively rotatable lapping elements. A further object of the invention is to provide a lapping machine having a pair of opposed relatively rotatable lapping elements which are relatively revolved to produce a combined rotary and planetary movement of the lapping elements relative to a work piece.

Another object of the invention is to provide a multiple work cage which is arranged to be automatically indexed to and from loading positions. A further object of the invention is to provide a lapping machine of the opposed wheel type in which a work cage for supporting a plurality of pieces of work to be lapped is moved automatically into an operative position between the lapping elements.

Another object of the invention is to provide a lapping machine with an electrically operated control whereby a work cage having a plurality of work pieces to be lapped is automatically moved or indexed into an operative position between the lapping elements, after which the lapping operation proceeds for a predetermined time interval as governed by an electrically operated control. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a fragmentary front elevation of a lapping machine embodying this invention, having parts broken away and shown in section, together with a hydraulic piping and wiring diagram of the control and actuating mechanisms therefor;

Fig. 2 is a vertical sectional view, taken approximately on the line 2—2 of Fig. 1;

Fig. 3 is a fragmentary sectional view, on an enlarged scale, taken approximately on the line 3—3 of Fig. 2; and

Fig. 4 is a fragmentary sectional view, on an

enlarged scale, of the reversing switch for controlling the cage positioning mechanism.

The improved lapping machine, as disclosed in the drawings, comprises a base 10 which supports a pair of opposed spaced lapping wheels 11 and 12 having opposed plane lapping surfaces arranged simultaneously to engage opposite sides of a work piece to lap the same. The lapping element 11 is mounted at the lower end of a vertically arranged rotatable spindle 13 which is rotatably journaled eccentrically within a rotatable sleeve 14. The spindle 13 and sleeve 14 are each provided with independent driving mechanisms so that the lapping wheel 11 may be rotated about the axis of the wheel spindle 13 and the sleeve 14 may be rotated about its axis of rotation to produce a combined rotary and planetary movement of the lapping wheel 11.

Similarly, the lower lapping wheel 12 is supported on the upper end of a rotatable spindle 15 which is rotatably and eccentrically journaled within a rotatable sleeve 16. The spindle 15 and the sleeve 16 are each arranged to be independently rotated so as to rotate the lapping wheel 12 about the axis of its supporting spindle 15 and to rotate the sleeve 16 about its axis of rotation so as to produce a combined rotary and planetary movement of the lapping wheel 12.

A driving mechanism is provided for rotating and revolving the lapping wheels 11 and 12. A variable speed electric motor 20 is mounted within the base 10 of the machine. A pulley 21 is mounted on the end of the motor drive shaft and is connected by means of a driving belt 22 with a pulley 23 which is mounted on the outer end of a rotatable shaft 24. The shaft 24 is journaled in a bearing 25 fixedly supported in the base 10 of the machine. A bevel gear 26 is mounted on the inner end of the shaft 24 and meshes with a bevel gear 27 which is in turn keyed to a vertically arranged rotatable shaft 28. The shaft 28 is journaled in bearings 29, 30 and 31 which are fixedly mounted within the base 10 of the machine.

The lower end of the shaft 28 is provided with a pulley 35 which is connected by means of a driving belt 36 with a larger diameter pulley 37. The pulley 37 is removably mounted on the lower end of the spindle 15 so as to rotate the lower lapping wheel 12. An idler pulley 38 is rotatably mounted on a stud 39 which is in turn supported by an idler bracket 40 to take up the slack and to properly tension the driving belt 36. The pulleys 35 and 37 may be readily changed to

facilitate rotating the lapping element or wheel 12 at a desired speed.

The upper lapping element 11 is similarly rotated either in the same or in the opposite direction from the lower lapping wheel 12. As illustrated in Fig. 2, a driving mechanism has been shown for rotating the lapping wheel spindle 13 and the lapping wheel 11 in the opposite direction from the lapping wheel 12. A gear 45 is keyed on the shaft 28 and meshes with a gear 46 which is keyed to a rotatable shaft 47. The shaft 47 is journaled in a bearing 48 in the base 10. A pulley 49 is removably keyed to the upper end of the shaft 47 and is connected by means of a driving belt 50 with a pulley 51 which is removably mounted on the upper end of the lapping wheel spindle 13 to rotate the spindle 13 and the upper lapping wheel 11 in a direction opposite to the rotation of the lower lapping wheel 12. An idler pulley 52 is rotatably supported on a shaft 53. The shaft 53 is supported on idler brackets 54 and 55 which are rotatably supported on the shaft 28.

If it is desired to rotate the spindle 13 and lapping wheel 11 in the same direction as the spindle 15 and lapping wheel 12, the pulley 49 may be removed from the shaft 47 and mounted on the upper end of the shaft 28 so as to drive the spindle 13 in the same direction as the spindle 15.

In order to secure the desired and predetermined lapping action, it is desirable to impart a planetary motion to the lapping wheels 11 and 12. This planetary movement is obtained by independently rotating the sleeves 14 and 16 about their respective axes. The vertical drive shaft 28 is provided with a driving gear 60 which is slidably keyed thereto and is held in adjusted position thereon by means of a set screw. The gear 60 meshes with a gear 61 which is rotatably supported on a stud 62. The gear 61 meshes with a gear 64 which, as illustrated, is formed by cutting elongated gear teeth formed in the periphery of the sleeve 14. The gear 64 is a wide faced gear having relatively long gear teeth to facilitate longitudinal or axial movement of the quill or sleeve 14 during movement of the upper lapping wheel 11 to and from an operative position. When the shaft 28 is rotated, it serves not only to transmit rotary motion through the belt 50 and pulley 51 to rotate the spindle 13 but also through the gears 60, 61 and 64 to rotate the sleeve 14 to impart a planetary or revolving movement to the lapping wheel 11 during rotation thereof.

Similarly, a gear 65 is mounted on the drive shaft 28. The gear 65 meshes with a gear 66 which is supported on a rotatable shaft 67. The shaft 67 is journaled in bearings 68 and 69 supported by the base 10. The gear 66 meshes with a gear 70 formed on the periphery of the sleeve 16. It will be readily apparent from the foregoing disclosure that when the shaft 28 is rotated, a rotary motion is transmitted by the belt 36 and pulley 37 to rotate the spindle 15 and the lower lapping wheel 12 about the axis of the spindle 15, and at the same time the gears 65, 66 and 70 serve to rotate the sleeve 16 so as to impart a planetary or revolving motion to the lapping wheel spindle 15 and the lapping wheel 12 during rotation thereof.

A fluid pressure system is provided for moving the lapping wheels 11 and 12 relatively toward and from each other. In the preferred form the upper lapping wheel is moved toward and from

the lower lapping wheel 12 by means of a pair of diametrically opposed fluid pressure cylinders 80 and 81 which are in turn fixedly mounted on the frame 82 which is fixed relative to the base 10. The cylinders 80 and 81 are provided with pistons 83 and 84, respectively. The pistons 83 and 84 are connected by piston rods 85 and 86 with a flanged plate 87 which is rotatably supported by a groove 88 formed in the lower end of the sleeve 14. The piston rods 85 and 86 are fixedly connected to the flanged plate by means of a plurality of nuts so that when the pistons 83 and 84 are moved within the cylinders 80 and 81, the piston rods 85 and 86 will cause a corresponding movement to be transmitted to the vertically movable sleeve 14, the spindle 13, and the lapping wheel 11.

Fluid for a fluid pressure system is supplied from a reservoir 90 formed as a box-like section within the base 10. Fluid is conveyed from the reservoir 90, through a pipe 91, by means of a motor driven fluid pump 92 which forces fluid under pressure through a pipe 93 to a reversing or control valve 94. The valve 94 is a balanced piston type valve comprising a valve stem 95 having formed integrally therewith a plurality of valve pistons 96, 97 and 98. A variable pressure relief valve 99 is connected with the pipe 93 and serves to maintain the desired operating pressure in the system. If the pressure within the hydraulic system becomes excessive, the pressure relief valve 99 opens and by-passes excess fluid under pressure through a pipe 100 into the reservoir 90.

Fluid under pressure from the pump 92 passing through the pipe 93 enters a valve chamber 101 located between the valve pistons 97 and 98 and, in the position of the valve shown in Fig. 1, passes outwardly through a pipe 102 into cylinder chambers 103 and 104 to cause a downward movement of the pistons 83 and 84 to move the upper lapping wheel 11 downwardly and serves to maintain the lapping wheel 11 in lapping engagement with the work pieces to be lapped during the lapping operation. During the downward movement of the pistons 83 and 84, fluid is exhausted from cylinder chambers 106 and 107, through a pipe 108, into a valve chamber 109 located between the valve pistons 96 and 97, and out through an exhaust pipe 110 into the reservoir 90.

A manually operable control lever 111 is provided for actuating the valve stem 95. The lever 111 is fixedly mounted on a rock shaft 112. A short arm or lever 113 is also fixedly connected with the shaft 112 and is connected at its other end with the valve stem 95. The valve stem 95 may be moved in either direction by means of the manually operable lever 111 to cause an upward or downward movement of the upper lapping wheel 11. In the preferred construction, a pull type electric solenoid 114 is operatively connected to the upper end of the valve stem 95 and is arranged so that when the solenoid 114 is energized, the valve stem 95 will be moved upwardly into the reverse position from that shown in Fig. 1. When the valve 94 is shifted into its uppermost position either by manual actuation of the lever 111 or by energization of the solenoid 114, fluid under pressure passing through the pipe 93 enters the valve chamber 109 located between the valve pistons 96 and 97 and passes through the pipe 108 into the cylinder chambers 106 and 107 to cause an upward movement of the pistons 83 and 84 so as to raise the lapping wheel 11 to

an inoperative position. During the upward movement of the lapping wheel 11, fluid within the cylinder chambers 103 and 104 exhausts through the pipe 102, through the valve chamber 101, and out through the pipe 110 into the reservoir 90.

In order to obtain a maximum production from the improved lapping machine, a multiple work cage is provided comprising work cages 115 and 116 each of which is rotatably supported by a longitudinally movable work table 117. The work cages 115 and 116 are disk-shaped members having a plurality of work receiving apertures simultaneously to support a plurality of work pieces 118 for a lapping operation. As shown in Fig. 1, the cage supporting table 117 is supported by a plurality of pairs of anti-friction rollers 119, 120 and 121 (Figs. 1 and 2) which ride within a groove 122 formed adjacent to the front edge of the machine and a correspondingly arranged set of rollers 119a, 120a and 121a having V-shaped peripheries (Figs. 2 and 3) which ride within a V-way 123 formed on the base 10 and which is arranged parallel to the grooved flat way 122.

As illustrated in Fig. 1, the work carrying cage 115 is in a loading position and the cage 116 is in an operative position between the lapping wheels 11 and 12. After the lapping operation has been completed on the work pieces supported in the cage 116, the upper lapping wheel 11 is raised and the table 17 indexed or moved toward the right into position 117a (Fig. 1) which moves the cage 116 toward the right to an inoperative or loading position 116a and at the same time shifts the cage 115 toward the right into an operative position between the lapping wheels 11 and 12.

A fluid pressure mechanism is provided for indexing the cage supporting table 117, comprising a fluid pressure cylinder 125 which is fixedly supported on the under side of the table 11 by brackets 126 and 127. Spaced pistons 128 and 129 are slidably mounted within the cylinder 125 and are connected by hollow piston rods 130 and 131, respectively, with hollow brackets 132 and 133, respectively. The brackets 132 and 133 are fixedly mounted on opposite ends of the base 10. A fluid pressure reversing or control valve 135 is provided for controlling the admission of fluid under pressure to opposite ends of the cylinder 125. The valve 135 is a piston type reversing valve comprising a valve stem 136 having formed integrally therewith a plurality of valve pistons 137, 138 and 139. A pipe 140 is connected between the bracket 132 and the valve 135, and a pipe 141 is connected between the bracket 133 and the valve 135.

In the position of the valve 135 (Fig. 1), fluid under pressure passing through the pipe 93 passes through a pipe 142 into a valve chamber 143 located between the valve pistons 138 and 139 and passes out through the pipe 140, through the hollow bracket 132, through the hollow piston rod 130, into a cylinder chamber at the left-hand end of the cylinder 125, to cause the cylinder 125 and table 117 to move to the extreme left-hand position, such as shown in Fig. 1. During the movement of the table 117 toward the left, fluid is exhausted from a cylinder chamber located at the right-hand end of the cylinder 125, through the hollow piston rod 131, through the hollow bracket 133, through the pipe 141, through a valve chamber 144, and out through a pipe 145 which exhausts into the

reservoir 90. When the valve stem 136 is shifted into the reverse position, the flow of fluid above described is reversed and fluid under pressure passing through the pipe 93 passes through a pipe 146, into the cylinder chamber 144, and through the pipe 141, the hollow bracket 133, the hollow piston rod 131, into the right-hand end cylinder chamber in cylinder 125 to cause the table 117 to move toward the right into position 117a (Fig. 1).

In order to shift the valve stem 136 automatically, an electric solenoid 147 is operatively connected to the left-hand end of the valve stem 136 and is arranged when energized to move the valve stem 136 to its extreme left-hand end position. Similarly, an electric solenoid 148 is operatively connected to the right-hand end of the valve stem 136 and serves when energized to cause the valve stem 136 to move into the position illustrated in Fig. 1.

In order to support the work pieces 118 when they are placed within the apertures of the work cage 115, a supporting plate 150 (Fig. 3) is provided which is supported on the base 10 by means of brackets 151 and 152. Similarly, a supporting plate 153 is supported on the base 10 by means of brackets 154 and 155 to serve as a support for work pieces when loaded into the cage 116 when it is in a loading position 116a at the right-hand end of its stroke (Fig. 3). In order that the work pieces may readily slide with the cages 115 and 116 from the supporting plates 150 and 153, respectively, onto the operative face of the lower lapping wheel 12, a plate 156 is provided which has a central aperture 157 which is slightly larger than the outer diameter of the lower lapping wheel 12. The plate 156 is provided with a stud 158 (Fig. 3) which rides in an elongated slot 159 formed in the plate 150 so that the plate 156 is free to move in a longitudinal direction but cannot rotate. The plate 156 is further provided with a plurality of downwardly extending studs 160 and 161 (only two of which have been shown) having rollers 162 and 163 rotatably supported at their lower ends. The rollers 162 and 163 are arranged so that their peripheries engage a peripheral surface 164 on the mounting plate for the lower lapping wheel 12. The rollers 162 and 163 riding upon the peripheral surface 164 as the lower lapping wheel 12 rotates and revolves, will impart a movement to the plate 156 so that the aperture 157 bears the same relationship with the periphery of the wheel 12 at all times during its lapping movement. It will be readily apparent from the foregoing disclosure that work pieces 118 in the cage 115 may be readily moved longitudinally by movement of the table 117 to position the cage 115 and work pieces 118 in an operative position between the lapping wheels 11 and 12.

A reversing switch 170 is provided having its casing fixedly mounted on the base 10. The switch 170 comprises an actuating stud 171 which is slidably mounted within the switch casing. The plunger 171 is provided with a pair of V-grooves 172 and 173. An arrow-pointed, spring-pressed plunger 174 is carried by the switch casing to hold the plunger 171 either in the left-hand end position so as to close a circuit between the wires or conduits 175 and 176 or in a right-hand end position to close a circuit between the wires or conduits 177 and 178. A pair of adjustably mounted table dogs 179 and 180 are supported by a T-slot 181 formed on the front edge of the table 117. The dogs 179 and 180 are ar-

ranged to engage the opposite end surfaces 182 and 183 of the switch actuating plunger 171 to reverse the switch at the ends of the stroke of the table or carriage 117. The electric reversing switch 170 is operatively connected in a manner to be hereinafter described to close the respective circuits to energize the solenoids 147 and 148. The end faces 184 and 185 of the casing of the reversing switch 170 serve in cooperation with the table dogs 179 and 180 positively to limit the longitudinal movement of the table 117 precisely to locate the work cages 115 and 116 in operative positions between the lapping wheels 11 and 12.

The rotatable sleeve 14 is rotatably supported in a vertically movable sleeve 190 which is slidably supported in a cylindrical bore 191 formed in the frame 82 which, as illustrated, is formed integral with the base 10 of the machine. The sleeve 190 is provided with a block 193 which serves as a support for a pair of adjustably mounted screws 194 and 195. The screw 194 is arranged in the path of the actuating roller of a normally open limit switch 196. Similarly, the screw 195 is arranged in the path of the actuating roller of a normally open limit switch 197.

With the parts in the position shown in Fig. 1, when the upper lapping wheel 11 moves upwardly to an inoperative position, the screw 194 engages the actuating roller and closes the limit switch 196 which is connected in series with the reversing switch 170 and the solenoid 147 to energize the solenoid 147 and thereby to shift the reversing valve stem 136 toward the left into the reverse position.

Similarly, the screw 195 is arranged on the downward movement of the upper lapping wheel 11 to engage the actuating roller of the limit switch 197 which operates to set an electrical time delay relay 200 in motion. The electric time relay 200 may be any standard time relay but in the preferred form may be a time delay relay known as the "Microflex" manufactured by the Eagle Signal Corporation of Moline, Illinois. The closing of the limit switch 190 serves through the time delay relay 200 to actuate a magnetic starter switch 201 to start the main driving motor 20 as the upper lapping wheel moves into engagement with the work pieces 118. A push button start and stop switch 202 is provided between the magnetic starter switch 201 and the source of power illustrated by the power lines 203. A relay switch 204 is connected between the power lines 203, the solenoid 114, and the time delay relay 200 and is arranged so that after a predetermined time interval has elapsed, as governed by the time relay 200, it will close a circuit to energize the solenoid 114 to shift the valve stem 95 upwardly and thus admit fluid under pressure to raise the upper lapping wheel 11. The time relay 200 is also operatively connected so that after a predetermined time interval and before the relay 204 is energized to energize the solenoid 114, the magnetic starter switch 201 is actuated to stop the main drive motor 20, after which the relay switch 204 energizes the solenoid 114 to shift the valve 94 so as to cause an upward movement of the upper lapping wheel 11 to an inoperative position so as to facilitate removing work pieces from an operative position between the wheels to an inoperative position while moving a fresh set of work pieces into operative relation between the lapping wheels.

The operation of this improved lapping machine will be readily apparent from the foregoing disclosure. Assuming the parts to be in the po-

sition illustrated in Fig. 1, that is, with the lapping wheels operatively engaging work pieces supported in the lapping cage 116, the lapping operation proceeds until the lapse of a predetermined time interval as governed by the time relay 200. After the time interval has elapsed, the time relay 200 serves through the magnetic starter switch 201 to break the circuit and thus stop the motor 20 to stop the rotation and planetary movement of the lapping wheels 11 and 12. After the lapping wheels have stopped, the time relay operates through the relay 200 to energize the magnet of the relay 204 to close a circuit so as to energize the solenoid 114 which shifts the valve stem 95 into an uppermost position so that fluid under pressure from the pump 92 passing through the pipe 93 enters the valve chamber 109 and passes through the pipe 108 to the cylinder chambers 106 and 107 to cause an upward movement of the gear pistons 83 and 84, respectively. This movement causes an upward movement of the lapping wheel 11 to move it to an inoperative position.

When the upper lapping wheel 11 approaches its uppermost position, the screw 194 engages the actuating roller of the limit switch 196 to close the switch to energize the solenoid 147 which serves to shift the reversing valve 136 into an extreme left-hand end position. In this position of the valve 135, fluid under pressure from the pump 92 passing through the pipe 93 passes through the pipe 146, the valve chamber 144, the pipe 141, the hollow bracket 133, and the hollow piston rod 131, into the cylinder chamber at the right-hand end of the cylinder 125 to cause the cylinder 125 together with the table 117 to move toward the right into position 117a (Fig. 1). The movement of the table 117 toward the right continues until the dog 179 engages the stop face or abutment 184 formed on the casing of the limit switch 178 which stops the table 117 in position 117a with the work carrying cage 115 located in an operative position between the lapping wheels 11 and 12. In this position of the parts, the work carrying cage 116 is moved into position 116a (Fig. 3), in which position the lapped work pieces 118 may be readily removed from the cage and the cage loaded with new work pieces to be lapped.

When it is desired to initiate the next lapping operation, the manually operable lever 111 is moved downwardly, that is, in a counterclockwise direction to shift the valve 94 into the position illustrated in Fig. 1 so that fluid under pressure from the pump 92 is conveyed through the pipe 93 to the valve chamber 101 and the pipe 102 into the cylinder chambers 103 and 104, respectively, to cause a downward movement of the lapping wheel 11 into an operative position. As the lapping wheel 11 approaches an operative position, the actuating screw 195 engages the actuating roller of the limit switch 197 to close the same. The closing of the limit switch 197 serves to close a circuit setting the time relay 200 into operation and at the same time serves to close a circuit through the magnetic starter switch 201 to start the motor 200 so as to start the rotary and planetary movement of the lapping wheels 11 and 12 to produce the desired lapping operation on the work pieces 118 for a predetermined time interval.

As above described, after the predetermined time interval has elapsed, the cycle as above described is repeated, that is, the rotation and revolution of the lapping wheels 11 and 12 is first stopped, after which the control valve 95 is shifted to an uppermost position to raise the lap-

ping wheel 11. As the lapping wheel approaches its uppermost position, the work table 17 is set in motion to index the cage 15 into the position illustrated in Fig. 1 where it may be unloaded and loaded with fresh work pieces to be lapped. The time interval between lapping operations is very short since it is merely necessary for the operator to wait until the next work cage has been indexed to an inoperative position, after which the control lever 11 may be instantly shifted to start the next operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a base, a pair of opposed rotatable lapping wheels, means simultaneously to rotate said lapping wheels, means relatively to move said wheels toward and from each other, a longitudinally movable table, a pair of spaced, freely rotatable work cages supported by said table, and an automatically actuated mechanism intermittently to traverse said table successively and intermittently to position said cages in an operative position between said lapping wheels.

2. In a lapping machine having a base, a pair of opposed rotatable lapping wheels, means simultaneously to rotate said wheels, means simultaneously to revolve said wheels about an axis offset relative to the axis of rotation, means relatively to move said wheels toward and from each other, a longitudinally movable table between said wheels, a pair of spaced, freely rotatable work cages on said table, and means intermittently to traverse said table successively and intermittently to position said cages in an operative position between said lapping wheels.

3. In a lapping machine having a base, a pair of opposed rotatable lapping wheels, means simultaneously to rotate said wheels, means relatively to move said wheels toward and from each other, a longitudinally movable table between said wheels, a pair of spaced, freely rotatable work cages supported by said table, and means actuated by and in timed relation with the separating movement of said lapping wheels to traverse said table successively and intermittently to position said cages in an operative position between said lapping wheels.

4. In a lapping machine as claimed in claim 1, the combination with the parts and features therein specified, of an electric motor to rotate said lapping wheels and a limit switch actuated by the approaching movement of said lapping wheels automatically to start said motor to rotate the lapping wheels for a lapping operation.

5. In a lapping machine in accordance with claim 1, the combination with the parts and features therein specified, of an electric motor simultaneously to rotate said lapping wheels, a limit switch actuated by the relative approaching movement of said lapping wheels to start said motor, thereby to rotate the lapping wheels, an electric time delay which is set in motion by the closing of said switch which is arranged automatically to stop said motor after the lap-

ping operation has proceeded for a predetermined time interval.

6. In a lapping machine as claimed in claim 1, the combination with the parts and features therein specified, of a hydraulic piston and cylinder to traverse said table to index and position said work cages, a reversing valve therefor, a solenoid operatively connected to each end of said reversing valve, a table actuated reversing switch operatively connected successively to render said solenoid operative, and means including a limit switch connected in series with said reversing switch which is actuated by the separating movement of said lapping wheels automatically to index said table successively to position the work cages in an operative position between the lapping wheels.

7. In a lapping machine having a base, a pair of opposed rotatable lapping wheels, means simultaneously to rotate said lapping wheels, means relatively to move said wheels toward and from each other, a longitudinally movable table, a pair of spaced, freely rotatable work cages supported by said table, an automatically actuated mechanism intermittently to traverse said table successively and intermittently to position said cages in an operative position between said lapping wheels, means automatically to start the rotation of said lapping wheels to initiate a lapping operation, and means automatically to stop the rotation of said lapping wheels after a predetermined time interval.

8. In a lapping machine having a base, a pair of opposed rotatable lapping wheels, means including an electric motor simultaneously to rotate said wheels, means relatively to move said wheels toward and from each other, a longitudinally movable table between said wheels, a pair of spaced, freely rotatable work cages supported by said table, means actuated by and in timed relation with the separating movement of said lapping wheels to traverse said table successively and intermittently to position said cages in an operative position between said lapping wheels, and means actuated by and in timed relation with the approaching movement of said lapping wheels automatically to start said electric motor to rotate said wheels.

9. In a lapping machine having a base, a pair of opposed rotatable lapping wheels, means including an electric motor simultaneously to rotate said wheels, means relatively to move said wheels toward and from each other, a longitudinally movable table between said wheels, a pair of spaced, freely rotatable work cages supported by said table, means actuated by and in timed relation with the separating movement of said lapping wheels to traverse said table successively and intermittently to position said cages in an operative position between said lapping wheels, means actuated by and in timed relation with the approaching movement of said lapping wheels automatically to start said electric motor to rotate said wheels, and means automatically to stop said motor and to separate said lapping wheels after a predetermined lapping operation.

10. In a lapping machine as claimed in claim 1, the combination with the parts and features therein specified, of an electric motor simultaneously to rotate and revolve the opposed lapping wheels, a hydraulic piston and cylinder to move one of said lapping wheels toward and from the other, a control reversing valve to admit fluid under pressure to either end of said cylinder,

a manually operable lever to shift said valve to move said lapping wheel to an operative position, an electric solenoid operatively connected to shift said valve to produce a separating movement of the lapping wheel, a limit switch actuated by movement of the lapping wheel to an operative position, and an electric time delay relay which is set in motion by the closing of said

switch to control the duration of the lapping operation, said time relay being arranged after a predetermined time interval to stop said driving motor and to energize said solenoid and thereby move said lapping wheels to an inoperative position.
